UNITED STATES PATENT OFFICE

162,480

WALLPAPER OR THE LIKE

James Seeman, Forest Hills, N. Y.

Application June 22, 1950, Serial No. 10,694

Term of patent 3½ years

(Cl. D59—10)

To all whom it may concern:

Be it known that I, James Seeman, a citizen of the United States of America, residing in Forest Hills, county of Queens, and State of New York, have invented a new, original, and ornamental Design for a Wallpaper or the like, of which the following is a specification, reference being had to the accompanying drawing, forming part thereof.

The figure on the drawing is a face view of wallpaper or the like, showing my new design.

I claim:

The ornamental design for a wallpaper or the like, substantially as shown.

JAMES SEEMAN.
